CLAIM

The ornamental design for a container for hand and body lotion as shown and described.

DESCRIPTION

FIG. 1 is an isometric view of a container for hand and body lotion illustrating an embodiment of our new design;

FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a bottom view thereof; and,

FIG. 8 is an expanded view thereof.

The broken lines in the drawings are included for the purpose of illustrating portions of the container for hand and body lotion and form no part of the claimed design. The additional, dash-dash broken lines in FIGS. 1 and 8, represent the boundary of the enlargement and form no part of the claimed design.
